(57) **CLAIM**

The ornamental design for a mobile power device as shown and described.

DESCRIPTION

FIG. 1 is a front, right and top perspective view of a mobile power device showing our design;

FIG. 2 is a rear, left and bottom perspective view thereof;

FIG. 3 is a front elevation view thereof;

FIG. 4 is a rear elevation view thereof;

FIG. 5 is a left-side elevation view thereof;

FIG. 6 is a right-side elevation view thereof;

FIG. 7 is a top plan view thereof;

FIG. 8 is a bottom plan view thereof;

FIG. 9 is a perspective view of another state of the mobile power device thereof; and,

FIG. 10 is an enlarged view of portion 10 shown in FIG. 2. The broken lines are included for the purposes of illustrating portions of the mobile power device that form no part of the claimed design.

1 Claim, 10 Drawing Sheets
